INFLATABLE SLED

Victor M. Solipasso, Sanger, Calif., assignor of one-fifth to Harvey A. Jacobsen, Fresno, Calif., and one-fifth to Ronald H. Metzler, Del Rey, Calif.

Filed July 11, 1966, Ser. No. 3,024

Term of patent 14 years

(Cl. D34—15)

FIG. 1 is a top plan view of an inflatable sled showing my new design.

FIG. 2 is a side elevation thereof, the opposite side of the inflatable sled being identical to the side shown.

FIG. 3 is a bottom plan view thereof.

FIG. 4 is a front elevation thereof.

FIG. 5 is a rear elevation thereof.

FIG. 6 is a perspective thereof.

The present application is a continuation-in-part of my co-pending application Serial No. D.83,735, entitled Inflatable Sled, filed February 8, 1965, and now abandoned.

I claim:

The ornamental design for an inflatable sled, as shown and described.
